TELEPHONE TRUNKING AND SUPERVISORY SYSTEM.

1,191,917.

Specification of Letters Patent.

Patented July 18, 1916.

Application filed February 26, 1907. Serial No. 359,406.

To all whom it may concern:

Be it known that I, WILSON L. CAMPBELL, a citizen of the United States of America, and resident of Chicago, Cook county, Illinois, have invented a certain new and useful Improvement in Telephone Trunking and Supervisory Systems, of which the following is a specification.

My invention relates to telephone systems, 10 and more especially to systems in which means are provided for enabling a calling subscriber to establish connection with the desired line, without the aid of operators.

Objects of my invention are to provide 15 means for enabling any subscriber to establish connection with a special service line, such, for example, as a line leading to one or more operators' positions, whereby the said calling subscriber may report trouble 20 or receive information or obtain such other service as may be desired; to provide a special service line having provisions for enabling the first operator thereon to transfer all incoming calls to the next operator, and 25 for enabling the second operator to transfer the calls to the third operator, and so on throughout the series of operators, according to requirements; to provide an arrangement by which a calling subscriber may ex- 30 tend connection from his line over one or more trunk lines to a connector, and may then cause the said connector to establish connection with a special service line leading to one or more operators, the said con- 35 nector being preferably what is commonly known as a rotary connector—that is to say, a connector which will automatically rotate like a trunk selector until it finds an idle line; to provide lamp signals for attracting 40 the attention of the operators on the special service lines, which lamp signals can be brought into operation by the calling subscriber when he presses his ringing key, said lamps being controlled by relays which 45 are responsive to the ringing current; to provide pilot lamps for the different operators' positions, one pilot lamp being common to all the operators who occupy first position on the group of special service lines, and 50 other pilot lamp being common to all operators who occupy second position on the group of special service lines, and so on throughout the series of positions on the said special service lines; and to provide cer- 55 tain details and features of improvement

and combinations tending to increase the general efficiency and serviceability of a system of this particular character.

To the foregoing and other useful ends, my invention consists in matters herein disclosed and claimed.

In the accompanying drawings, Figure 1 is a diagram shewing a substation A connected with a central office comprising a central battery B having, preferably, its positive terminal grounded at G, and automatic switches C, D and E, in connection with which I have elected to explain my invention. The switch C is commonly known as a first-selector; the switch D as a second-selector, and the switch E as a connector. At F is represented a busy-signaling machine, and at H is shown a ringer generator.

In Fig. 2, which is a diagram, are shown several manual circuits comprised in my invention and located at the central office, at which place I, J and K represent, respectively, a first, second and a last operator's position. Obviously, however, other such operators' positions may be inserted, as, for example, between the positions J and K, substantially as position J is placed between I and K. In connection with these manual circuits there is shown a night alarm arrangement L. The keys a, b and c, whereby the incoming trunk line may be extended from one operator's position to another, are shown in normal position. The arrangement of the system is such that the attendant at position I may, by operating the springs at the left of key a, extend the trunk line (shown leading from Fig. 1 to Fig. 2, and which, while key a is normal, terminates at position I) to the operator at J where the signal will be received without signaling position I. Similarly the operator at J may operate the springs on the left of key b and in turn transfer the incoming trunk line to the next position.

Figs. 1 and 2 taken together show means whereby an automatic subscriber may establish connection with a trouble-recording or other operator's board.

The substation A may be of any suitable type, and comprises, for example, a receiver 105 2, switch-hook 3, induction-coil 4 (which coil consists of the primary winding 5 and secondary winding 6), transmitter 7, local battery 8 and the ringer 9. In addition to the above-mentioned parts an impulse wheel 110

10 is provided which has the usual vertical impulse teeth 11 that are adapted to operate the vertical impulse spring 12. The impulse wheel carries the rotary impulse tooth 13 which operates the rotary impulse spring 14. The switch-hook has radiating from its body a number of cam-arms 15, 16 and 17, and is pivotally secured to the keyboard (not shown) at the point 18 about which it 5 operates when the receiver is removed. The operation is produced by a spring (not shown) for the purpose of changing certain circuit connections to be disclosed. The cam-arm 15 controls the so-called locking arm 19. After the dial is rotated the locking arm 19 occupies the position shown at substation A, the mechanical operations of which are well known; and at the same time the coöperating ground springs 20 and 21 10 engage, thus placing the ground post 22 in contact with the substation ground G', whereby, when the subscriber releases the dial after rotating it as described, the vertical impulse teeth 11 will then cause the vertical impulse spring 12 to come into contact with the ground post 22; and immediately after, the rotary impulse tooth 13 causes the rotary impulse spring 14 to come 15 into contact with the same ground post 22. When the switch-hook is down the cam-arm 17 maintains a contact with the spring 23, thereby bridging the ringer 9 across the line. The springs 24 and 25, and 26 and 27 are then disengaged, and the primary circuit including the winding 5 in series with the transmitter 7 and local battery 8 is interrupted by the separation of the springs 26 and 27. The disengagement of the springs 24 and 25 removes the secondary 20 winding 6 in series with the receiver 2 from across the line. The signaling device whereby a subscriber may signal another after a connection has been established comprises a push-button 28 and a spring 29, which latter normally engages the contact point 30; but when the push-button 28 is pressed the spring 29 leaves the contact point 30 and 25 engages the contact point 31 which is connected with the substation ground G'. Means whereby the subscriber may release 30 the central station apparatus brought into service comprises three springs 32, 33 and 34, known as the release springs and so controlled by the cam-arm 16 that when the switch-hook descends the three release 35 springs are brought into contact, thereby grounding both of the subscriber's line conductors simultaneously.

The first-selector C is of the well-known type disclosed in United States Patent No. 815,321, granted March 13, 1906, to Keith, Erickson & Erickson, and upon referring to Fig. 1 its various relays and magnets will at once be recognized. As illustrated, 61 65 and 62 indicate the vertical and rotary line

relays by means of which the switch is operated; 61^a indicates the bridge-cut-off relay for controlling the connection between said line relays and the battery; 37^a indicates the vertical magnet for raising the shaft 70 vertically; 38^a indicates the rotary magnet for rotating the shaft and shaft wipers; 39^a indicates the private magnet by means of which the side switch is controlled; 41^a indicates the release magnet for restoring the 75 switch after operation; and 40^a indicates the back-release relay by means of which the selector is released after the side switch passes to third position.

The second-selector D is quite similar to 80 the first-selector C and comprises vertical and rotary line relays 35 and 36, respectively, vertical and rotary magnets 37 and 38, private magnet 39, release relay 40 and a release magnet 41. Furthermore, it will 85 be noticed that the bridge-cut-off relay of the second-selector does not appear, the line relays 35 and 36 being connected directly to the battery lead; also, that the line relays 35 and 36 are provided with the trunk-release 90 springs 42 and 43 which are similar to the release spring of the connector disclosed in United States Patent No. 815,176, granted March 13, 1906, to Keith, Erickson & Erickson. 95

The connector switch E, commonly known as a rotary connector, is a modification of the connector disclosed in the said connector patent. The vertical and rotary line relays 44 and 45, respectively, are provided with the usual connector springs. The vertical and rotary magnets 46 and 47 are under the control of the vertical line relay 44. In addition, the rotary magnet 47 is provided with the interrupter spring 48 by 105 means of which the said connector may be automatically rotated (like the first-selector) when the private wiper engages grounded contact points. Hence, with this provision, whereby the connector may be automatically 110 rotated in addition to being rotated in the usual manner, the rotary element combines the rotary characteristics of the first-selector and the connector disclosed in both of said patents. A new feature of this connector is 115 the private relay 49 which is controlled by the rotary line relay 45. The former in turn controls the private magnet 50 under certain conditions, as will be more fully explained hereinafter. The function and operation of the back-bridge relays 51 and 52 are well-known; also, the ringer relay 53 and the release magnet 54 are controlled and operated as explained in the said connector patent. 120

At the signal-receiving board the operator's set (Fig. 2) comprises a key a which is adapted to operate the group springs, as shown. The relay 55 is provided for closing a circuit through the signal lamp 56 130

which indicates to the attendant that a subscriber has seized the allotted line. The pilot relay 57 is common to a group of trunk line signal lamps, of which group lamp 56 is a member. The said relay, when energized, operates to close a circuit through the pilot lamp 58. At *d* is shown an operator's telephone set. At the second operator's position *J* is shown a duplicate of the apparatus and circuits of the position *I*. The only difference in the last position *K* is found in the key *c*; for there the left-hand group of springs, whereby the trunk line is extended to the next succeeding position, is omitted.

Assuming that the automatic subscriber *A* wishes to communicate with the central office, he may do so by calling a number that will place him in connection with the rotary connector *E*, which connector he then operates in order to establish connection with a trunk line leading to some operator or sets of operators. His object in doing so may be to report trouble, obtain information, call for toll connection, or any other similar object. To start with, it will be assumed that the number of the line that leads to the operators' sets, shown in Fig. 2, is 8111. The number 8111, however, may be given to a set of lines, each line terminating in a different manual set, such as the one shown in Fig. 2. The object of such an arrangement is that if the first line of group 8111 is busy the rotary connector *E* will automatically rotate until it finds the first idle line, in the same manner that the selector switches operate when they are selecting trunks. Obviously, such an arrangement is necessary in an exchange where a number of subscribers are liable to call very close together. It will be obvious, furthermore, that the connector *E* may be provided with a number of such groups, each of which may be given a separate and distinct number, such as 8115, 8121, or any other number which is applicable to such a connector, each of which groups may be used for an absolutely different and distinct purpose. With the arrangement shown in Fig. 1 the last contact of the group to which the line leading to Fig. 2 belongs is connected with the *busy* machine *F*, so that if all the lines of that particular group are busy the calling subscriber may, when the connector passes onto the last set of contacts, receive the busy signal. When the subscriber at substation *A* starts to call the group 8111, he operates the dial for the first digit 8, as a result grounding the vertical and rotary line conductors 59 and 60, whereby the vertical and rotary line relays 61 and 62 become energized and operate in the well-known manner, with the result that the first-selector side switch passes to third position, and that the selector switch shaft wipers 63, 64 and 65 are placed in contact with the con-

ductors leading to the second-selector *D*. Now when the dial is operated for the second digit 1, the vertical and rotary line relays 35 and 36, respectively, of the second-selector *D* alternately energize and operate to extend the subscriber's line conductors 59 and 60 to the connector *E*, by way of the shaft wipers 66 and 67, substantially as the first-selector *C* operated to extend the line conductors 59 and 60 to the selector *D*. 75

The ground impulses given to the line conductors 59 and 60, respectively, for the last two digits 1 and 1 are effective in operating the connector *E*. When the conductor 59 is grounded for the third digit 1 the vertical line relay 44 becomes energized and operates to place the springs 68 and 69 in contact, whereby an energizing circuit is completed in the well-known manner through the vertical magnet 46, with the result that the shaft wipers 70, 71 and 72 are raised one step. When the rotary line relay 45 energizes as a result of the ground impulse to the rotary line conductor 60, the springs 73 and 69 engage and close a circuit through the private relay 49 extending from ground *G*² through the springs 69 and 73, through the private relay 49 to the battery lead 74, thence through battery *B* and to ground *G*. The private relay, upon energizing, operates in turn to disengage the springs 75 and 76, and to thereby place the springs 77 and 78 in contact. The engagement of the springs 77 and 78 closes an energizing circuit through the private magnet 50 extending from ground *G*³ through the springs 77 and 78, through the private magnet 50 to the battery lead 74, thence through battery *B* and to ground *G*. The private magnet operates to permit the side switch wipers 79, 80, 81 and 82 to pass from first to second position, whereby the rotary magnet 47 comes under the control of the vertical relay 44. The last digit being 1, the vertical line relay 44, upon energizing, closes an energizing circuit through the rotary magnet 47 which operates to rotate the shaft wipers 70, 71 and 72 onto the first contact of the first level. Now when the last rotary impulse operates the rotary line relay 45 one of two results occurs, namely the release of the side switch from second to third position at once, or the connector shaft is automatically rotated until an idle line is found, if the private wiper 72 finds the first line busy. This is brought about as follows: When the private relay 49, and in turn the private magnet 50, energize and operate, as previously explained, the energizing circuit through the private magnet is maintained after the relay 49 deenergizes, said circuit extending from the grounded private contact point 72, side switch wiper 82, contact point 83, private magnet spring 84 and 85, through the winding of the private

magnet 50 to the battery lead 74, thence through battery B and to ground G. The private magnet thus remains energized and retains the side switch in second position as long as the wiper 72 engages a busy or grounded contact. Furthermore, when the private magnet thus energizes, the spring 86 is shifted out of engagement with the spring 87 and into engagement with the spring 88, whereby a new energizing circuit is completed through the rotary magnet 47. This circuit extends from ground G⁴ to the interrupter springs 48, private relay springs 76 and 75, private magnet springs 88 and 86, side switch wiper 81, contact point 89, rotary magnet 47 to the battery lead 74, thence through battery B and to ground G. The connector now operates to rotate automatically as long as the shaft 20 wiper engages grounded contact points. When the shaft wiper 72 leaves the last busy contact the circuit through the private magnet is broken, whereby the said magnet deenergizes, breaks the circuit through the rotary magnet 47 and permits the side switch to pass to third position, extending the line conductors 59 and 60 to the trunk conductors 90 and 91, respectively, which latter lead to the toll-board 25 or desk equipped with my signal-receiving apparatus, as shown in Fig. 2.

When the subscriber at substation A presses the signaling button 28 the ringer relay 53 becomes energized in the well-known manner, and operates to bridge the ringer generator H across the trunk conductors 90 and 91, whereby a signaling current is transmitted from the springs 92 and 93 to the side switch wiper 79, contact point 94, shaft wiper 70, vertical conductor 90, through the springs 95 and 96, springs 97 and 98, winding 99 of the lamp relay 55, through the springs 100 and 101, 103 and 102 to the rotary trunk conductor 91, shaft 40 wiper 71, contact point 104, side switch wiper 80, ringer relay springs 105 and 106, thence to the generator H. The signaling current in passing through the winding 99 energizes the relay 55, which operates to 45 close the springs 107 and 108 in contact. The engagement of the springs 107 and 108 completes an energizing circuit through the locking winding 111 of the relay 55 and also through the signal lamp 56 in series with the 50 pilot relay 57. The circuit through the locking winding 111 extends from ground G⁵ to the springs 109 and 110, springs 107 and 108, through the winding 111, conductor 112 to the night alarm switch 113, to the battery 55 lead 74, thence through battery B and to ground G. The operator in response to the signal operates the key a in such a manner that the springs 97 and 98, 100 and 101, and 109 and 110, disengage, and the springs 97 and 116, and 101 and 117 engage. The dis-

engagement of the springs 109 and 110 breaks the energizing circuit through the lamp 56 and the locking winding 111. The engagement of the springs 97 and 116, and 101 and 117 bridges the operator's telephone set d across the trunk conductors 90 and 91, thus connecting with the calling subscriber at substation A. The subscriber at substation A and the operator at I may then communicate over a circuit shown by the heavy lines. If for any reason it is desired that operator J shall take charge of all calls coming in on the trunk conductors 90 and 91, the operator at position I operates the key a so that the springs 96 and 102 disengage the springs 95 and 103 and engage the springs 118 and 119, respectively, thereby disconnecting the line from position I and extending the conductors 90 and 91 to the second position J. Now when the line is seized the signal will be received at position J and the signal lamp 120, relay 121, pilot relay 122 and pilot lamp 123 will operate, as explained in connection with position I. Furthermore, the line may in turn be extended to position K by the operation of the key b, so that the springs 124 and 125 disengage from the springs 126 and 127 and engage the springs 128 and 129, respectively, whereby the line is disconnected from the position J and again extended to the position K. The signaling current now passes from the conductor 90 through the springs 96 and 118 of key a, springs 124 and 128 of key b, springs 130 and 131 of key c, winding 132 of relay 133, springs 134 and 135, springs 129 and 125 of key b, springs 119 and 102 of key a to the conductor 91. The relay 133, upon energizing, closes a circuit through the locking winding 136 of the relay 133, and a circuit through the pilot relay 137 in series with the signal lamp 138. The locking circuit through the winding 136 extends from ground G⁷ through the springs 139 and 140, springs 141 and 142, winding 136 of the relay 133, conductor 112 (assuming that the night alarm switch 113 occupies the position shown by dotted lines) through the night alarm relay 143 to the battery lead 74, thence through battery B and to ground G. The circuit through the lamp 138 extends from ground G⁷ through the springs 139 and 140, and 141 and 142, lamp 138, pilot relay 137, conductor 112, thence to the battery B through the night alarm relay, as previously traced. The pilot relay 137 operates to close the springs 144 and 145 in contact, whereby a circuit through the pilot lamp 146 is closed. The night alarm relay 143, upon energizing, closes the springs 147 and 148 into contact, and a circuit is thereby closed through the night signal bell 149. When the key c is operated the springs 130 and 135 disengage from the springs 131

- and 134 and engage the springs 150 and 151, respectively, whereby the lamp relay 133 is removed from across the extended line and the operator's set *e* is bridged instead. Furthermore, the springs 140 and 139 disengage, and the circuit through the signal lamp 138 and locking winding 136 is broken, thus permitting the lamp relay 133, the pilot lamp relay 137 and the night alarm relay 143 to return to normal position. It will be understood, of course, that the night alarm relay 143 (which may be cut in and out of the circuit by the switch 113) may or may not be used, as desired, the object of such provision being well known. The release of the central office switching apparatus is brought about when the calling subscriber restores the receiver and presses the release springs 32, 33 and 34 into contact, whereby the line conductors 59 and 60 are grounded simultaneously, with results that are well known. The pilot lamps 58, 123 and 146, it will be understood, may be controlled from the corresponding operators' position, from the several boards in the exchange, similar to the board shown in Fig. 2. For example, if the exchange is provided with ten trunks, each similar to the one having the conductors 90 and 91, and if each trunk is provided with an equipment similar to the one shown in Fig. 2, then the pilot lamp 58 may be operated whenever a call comes in to any one of the operators I of the various boards. If any of the trunk lines are extended to the operator J, the pilot lamp 123 may be operated when a call comes in to any operator J; and if any of the lines are extended to the operator K, the pilot lamp 146 may be operated whenever a call comes in to any one of the operators of the last position.
- The relays may be of any suitable resistance, but good results have been obtained when the lamp relays 55, 121 and 133 are wound to a resistance of five hundred ohms in each winding, and the pilot lamp relays 57, 122 and 137 and the night alarm relay 143 to a resistance of one and eight-tenths ohms each.
- From the foregoing it will be seen that a calling subscriber extends connection from his line over one or more trunk lines to a connector which is capable of picking out an idle special service line. On this special service line are one or more operators' positions, and each operator, except the last, of course, can transfer all incoming calls to the next operator, according to requirements. It will be understood, of course, that the said connectors can be employed on a percentage basis—that is to say, it will be understood that the connectors can be less in number than the total number of subscribers. It will also be understood that with such an arrangement the second-selectors will be less
- in number than the total number of subscribers, while the total number of first-selectors will be the same as the total number of subscribers, inasmuch as first-selectors are employed as individual switches for the different subscribers. Each connector, as explained, is adapted to rotate like a trunk selector until it finds an idle special service line.
- What I claim as my invention is:
1. A telephone system comprising a special service line, a plurality of operators' positions on said line, automatic means by which a calling subscriber extends connection to said line, and a switch at one position for transferring incoming calls to another position.
  2. A telephone system comprising a special service line, automatic means by which a calling subscriber extends connection to said line, a plurality of operators' positions on said line, and one or more switching devices by which each operator, except the last, may transfer incoming calls to the next operator.
  3. A telephone system comprising a special service line, a connector adapted to make connection with said line, automatic means for trunking a calling subscriber into connection with said connector, means by which the subscriber controls the connector to establish connection with the special service line, a plurality of operators' positions on said line, and means for transferring incoming calls from one position to another.
  4. In a telephone system, the combination of a special service line, a plurality of operators' positions on said line, means by which each operator, except the last, may direct the incoming calls to the next operator, an automatic connector adapted to connect with said line, automatic means for trunking a calling subscriber into connection with said connector, and means by which the subscriber controls the connector to complete connection with the said line.
  5. A telephone system comprising a special service line, a relay having two windings one of which is normally bridged across the said line, a battery, a local circuit including said battery and the other winding of the relay, said relay controlling said local circuit, circuit controlling means by which the calling subscriber projects current onto the line to initially energize said relay, and automatic progressively movable switching apparatus by which the calling subscriber extends connection to said line prior to the energizing of the relay.
  6. A telephone system comprising a special service line, a plurality of operators' telephones on said line, normally disconnected therefrom, a lamp signal for each telephone, means by which each operator automatically retires her allotted signal.

when she connects her telephone with the line, automatic means by which a calling subscriber extends connection to said line, and means by which one operator may direct the incoming calls to the next operator.

7. In a telephone system, the combination of a group of special service lines, a plurality of operators' positions on each line, automatic means for trunking a calling subscriber into connection with one of said lines, individual signals for the operators, a pilot lamp common to all operators occupying first positions on said lines and a pilot lamp for each additional group of operators occupying like positions on said lines.

8. In a telephone exchange system, the combination of a line, a plurality of operators' or attendants' telephones on said line, a visual signal for each telephone, a calling subscriber's line, automatic means for connecting the calling line with the other said line, parallel circuits for said visual signals, relay means controlling said circuits, and means by which one operator or attendant may direct the incoming calls to the visual signal of the next operator.

9. In a telephone exchange system, the combination of a line, a plurality of operators' or attendants' telephones on said line, a call-receiving device for each telephone, a calling subscriber's line, automatic means for connecting the calling line with the said other line, and means by which one operator may disconnect from the line and direct all incoming calls to the next operator.

* 10. In a telephone exchange system, the combination of a line, a calling subscriber's line, automatic means by which the calling subscriber connects his line with the said first-mentioned line, a plurality of operator's telephones on said first-mentioned line, a call-signal associated with each telephone, and means by which one operator may direct the incoming automatic calls to the next operator.

11. In a telephone system, a line with a plurality of operators' or attendants' positions thereon, means to automatically extend connection to said positions, the line being normally open at each position, and means for closing the line at each position and thus successively transferring calls from one operator to the next.

55 12. In a telephone system, a line, a plurality of call-receiving positions on said line, means to automatically extend connection to said positions, the line being normally open at each position, means for extending the line from one position to another to transfer incoming calls.

13. In a telephone system, a plurality of trunk lines, a relay bridged across each trunk and individual thereto, a signal controlled

by each relay, a relay common to a plurality of trunks and controlled by all of said first-mentioned relays, a supervisory signal controlled by said last-mentioned relay, a source of current for operating said individual relays, and a progressively movable switching device for controlling connection from said source of current for operating said relays.

14. In a telephone system, a plurality of trunk lines, a plurality of operators' sets associated with each trunk line, a relay bridged across each trunk and individual thereto, a supervisory signal controlled by said relay, a second relay controlled by a plurality of said first-mentioned relays, a second supervisory signal controlled by said last-mentioned relay, a source of current for operating said bridged relays, and progressively movable automatic switching apparatus for controlling connection from said source of current for operating said relays.

15. A telephone system comprising a special service line, a connector adapted to make connection with said line, automatic means for trunking a calling subscriber into connection with said connector, circuit means by which the subscriber controls the connector to establish connection with the special service line, a plurality of operators' positions on said line, and circuit means for transferring incoming calls from one position to another.

16. In a telephone system, the combination of a special service line, a plurality of operators' positions on said line, circuit means by which each operator, except the last, may direct the incoming calls to the next operator, an automatic connector adapted to connect with said line, automatic means for trunking a calling subscriber into connection with said connector, and circuit means by which the subscriber controls the connector to complete connection with the said line.

17. A telephone system comprising a special service line, a plurality of operators' telephones on said line, normally disconnected therefrom, a lamp signal for each telephone, circuit means by which each operator automatically retires her allotted signal when she connects her telephone with the line, automatic means by which a calling subscriber extends connection to said line, and circuit means by which one operator may direct the incoming calls to the next operator.

18. In a telephone exchange system, the combination of a line, a plurality of operators' or attendants' telephones on said line, a visual signal for each telephone, a calling subscriber's line, automatic means for connecting the calling line with the other said line, parallel circuits for said visual signals, relay means controlling said circuits, and

circuit means by which one operator or attendant may direct the incoming calls to the visual signal of the next operator.

19. In a telephone exchange system, the combination of a line, a plurality of operators' or attendants' telephones on said line, a call-receiving device for each telephone, a calling subscriber's line, automatic means for connecting the calling line with the said other line, and circuit means by which one operator may disconnect from the line and direct all incoming calls to the next operator.

20. In a telephone exchange system, the combination of a line, a calling subscriber's line, automatic means by which the calling subscriber connects his line with the said first-mentioned line, a plurality of operators' telephones on said first-mentioned line, a call-signal associated with each telephone, and circuit means by which one operator may direct the incoming automatic calls to the next operator.

21. In a telephone exchange system, the combination of a line, a plurality of operators' or attendants' telephones on said line, a visual signal for each telephone, a calling subscriber's line, automatic means for connecting the calling line with the other said line, parallel circuits for said visual signals,

relay means controlling said circuits, and means by which one operator or attendant may direct the incoming calls to the visual signal of the next operator.

22. In a telephone exchange system, the combination of a line, a plurality of operators' or attendants' telephones on said line, a call receiving device for each telephone, a calling subscriber's line, automatic means for connecting the calling line with the said other line, and means by which one operator may disconnect from the line and direct all incoming calls to the next operator.

23. In a telephone exchange system, the combination of a line, a calling subscriber's line, automatic means by which the calling subscriber connects his line with the said first mentioned line, a plurality of operators' telephones on said first mentioned line, a call signal associated with each telephone, and means by which one operator may direct the incoming automatic calls to the next operator.

Signed by me at Chicago, Cook county, Illinois, this 20th day of February, 1907.

WILSON L. CAMPBELL.
